SQUARE BOTTOM BAG

John F. Ames, Selma, Ala.; Evelyn H. Ames
executrix of said John F. Ames, deceased

Application December 7, 1937, Serial No. 178,585

5 Claims.

(Cl. 229—58)

This invention relating as indicated to a bag is more particularly directed to a square bottom bag. This term as used in the art designates a bag in which the bottom when filled extends at right-angles to the front and rear portions, or body portion, and is not used to denote the cross-section of the bag, which may be square, rectangular, circular or triangular.

In the past difficulty has been encountered in the manufacture of square bottom bags because the bottom portions of any bag require considerable folding and it is impossible to fold relatively stiff material, such as heavy paper, which is ordinarily required. On the other hand if light weight paper is used which folds readily to form the bottom, such material will not stand the ravages of shipment and distribution. In order to overcome this difficulty and to provide a bag which is very inexpensive I have combined a body portion of paper or the like with a bottom portion of flexible strong material, preferably cloth or fabric but not necessarily so. It is to be understood, however, that I am not to be restricted to cloth per se as other flexible materials may be advantageously used, provided such materials are inexpensive, relatively strong as compared to the paper body, and easily folded.

Heretofore the demand for a strong container has been met by supplying cardboard cartons which are much more expensive than paper bags. In the present instance the composite bag of paper and cloth can be made up with any desired strength. That is, relatively heavy unbendable paper can be used with a cloth bottom the total cost being considerably under that of a cardboard carton.

To the accomplishment of the foregoing and related ends, said invention, then, consists of the means hereinafter fully described and particularly pointed out in the claims; the annexed drawing and the following description setting forth in detail one product constituting, however, but one of the various applications of the principles of my invention.

In said annexed drawing:

Figure 1 is a perspective view of a completed bag with the top and bottom portions slightly distorted in order to show the parts.

Figure 2 is a partial perspective view of the bottom of a completed bag with parts slightly distorted.

Figure 3 is a sectional view of the upper portion of a bag when the same is partially expanded.

Figure 4 is a plan view of the bag blank with the bottom portion attached thereto.

Figure 5 is a sectional view similar to Figure 3 of a modification; and

Figure 6 is another perspective view similar to Figure 2 of a modification.

Referring now to the drawing, it will be seen that the body portion of the bag is made from a blank consisting of a front portion 1, rear portion 2, side portions 4 and 5, side portions 3 and 6, the side portion 3 having a flap 7 which is pasted or otherwise secured to the side portion 6. The crease lines 12, 13, 14, 15, 16, 17 and 18 separate the various portions and permit the bag to be folded in a flat condition. The small flap 8 shown in Fig. 4 extends upwardly from the rear portion 2 and is designed to be folded outwardly as shown more clearly in Fig. 3. Flap 8 is integral with the body portion and subsequent to the attachment of flap 7 on the side of the bag, the flap 8 is turned outwardly away from the opening of the bag to cover a Fig. 3. Flap 8 is integral with the body portion and subsequent to the attachment of flap 7 on the side of the bag, the flap 8 is turned outwardly away from the opening of the bag to cover a soft metal strip 11 as shown, or it may be folded inwardly (not shown).

The bottom portion 9 of relatively strong flexible material such as fabric or cloth is preferably secured to the paper blank by a line of stitching 10. It is to be understood, however, that this bottom portion 9 may be secured to the body portion by pasting, stapling, or where an extremely tight construction is desired, the bottom portion will be adhesively secured to the body portion as well as being stitched thereto.

The bag is preferably made by attaching the bottom portion 9 to the paper blank while said blank is in a flat condition. The next step is to then attach the flap 7 to the side portion 6 which can be done in any desired manner such as pasting, stitching and the like. After pasting flap 7, side portions 4 and 5, side portions 3 and 6 are folded inwardly leaving exposed only rear portion 2 and front portion 1. Subsequent to the placing of the side portions in and leaving exposed only front portion 1 and rear portion 2, the bottom stitch 10 is made, thus closing the bottom. The flap 8 is then turned outwardly and over the metal strip 11 leaving flap 8 enclosing metal strip 11 upon the rear portion 2, and the bag is complete ready to receive its contents. The step of filling the bag is rendered quite easy because of the provision of the flexible

bottom, it being merely necessary to drop the material into the bag which readily expands the bottom into its proper shape. It should be noted that a bag having a paper bottom cannot be as easily filled as my bag, because paper folds or creases do not readily expand.

In the method just described I have stated that the flap 8 is turned outwardly and downwardly over the metal strip 11 after the flap 7 has been attached to the side portion 6 but it will be understood that this step may be taken prior to pasting the flap 7 to the side portion 6.

In the modification shown in Fig. 5 the top portion is intended to be stitched or stapled and where fine material, such as sugar, salt and the like, are contained in the bag, the flaps 20 and 21 both projecting downwardly, form a valve which prevents sifting of the material. This is especially important where a paper bag is employed as care must be taken with the stitching because if the stitches are too close together the upper portion will become detached from the lower portion and if the stitches are too far apart the material will sift through. The provision of these flaps renders the exact placement of stitches relatively unimportant as long as they are not too close together.

In Fig. 6 I have shown a modification of the bag bottom shown in Figs. 1 and 2 and in this instance I use crepe paper 9' which is sufficiently strong for certain usage and is cheaper than cloth. It will readily unfold and except for the difference in tensile strength and appearance is just as satisfactory as cloth.

It is to be noted that the seams 40 and 40' of Figs. 1, 2 and 6 are shown distorted or extending outwardly for purposes of illustration only. In practice, just as soon as these bags have received their contents the bottom portions will present a smooth plane surface due to the weight of such contents and the flexibility of such bottom. Seams 40 and 40' are shown as being stitched but it will, of course, be understood that the seams may be made by stapling or pasting.

The crepe paper is, of course, more flexible than ordinary calendered paper out of which bags are customarily made but at the same time has requisite tensile strength to withstand the shocks and strains encountered in shipping.

It will now be seen that I have provided a bag which is suitable to receive products such as sugar, salt, rice, etc. and one which can be handled quite carelessly because the body portion can be made of very strong inflexible paper, whereas the bottom portion is made of a still stronger material which is easily folded thus providing the requisite strength in all portions of the bag.

It will also be seen that a wide choice of bag strengths is provided as the body of the bag may be made of any grade or thickness of paper depending upon the product that is to be shipped.

It will further be seen that the cost of a strong

bag is markedly reduced since paper comprises about 90% of the composite bag which holds the cost to a minimum, yet there is no limitation upon the strength or thickness of paper.

5 Other modes of applying the principle of the invention may be employed, change being made as regards the details described, provided the features stated in any of the following claims, or the equivalent of such, be employed.

10 I therefore particularly point out and distinctly claim as my invention:

1. A bag of the character described comprising front, rear and side portions and a bottom portion, said front, rear and side portions being composed of relatively stiff, single ply paper and said bottom portion being composed of a material that is more flexible than ordinary calendered paper but which possesses requisite strength, said bottom being closed by uniting said front and rear portions with a part of said side portions folded therebetween.

2. A bag of the character described comprising front, rear and side portions and a bottom portion, said front, rear and side portions being composed of paper and presenting substantially smooth flat surfaces, said bottom portion being composed of a material that is more flexible than ordinary calendered paper but which possesses requisite tensile strength, said bottom portion being stitched to the interior surfaces of said other portions, said bottom being closed by uniting said front and rear portions with a part of said side portions folded therebetween.

3. A bag of the character described comprising front, rear and side portions and a bottom portion, said front, rear and side portions being composed of paper and presenting substantially smooth flat surfaces, said bottom portion being composed of a material that is more flexible than ordinary calendered paper but which possesses requisite tensile strength, said bottom portion being adhesively secured to the interior surfaces of said other portions, said bottom being closed by uniting said front and rear portions with a part of said side portions folded therebetween.

4. A bag of the character described comprising front, rear and side portions and a bottom portion, said front, rear and side portions being composed of relatively stiff, single ply ordinary calendered paper and said bottom portion being composed of crepe paper, said bottom being closed by uniting said front and rear portions with a part of said side portions folded therebetween.

5. A bag blank comprising a front portion, a rear portion, an overlapping portion and side portions, all of said portions having interior and exterior surfaces and lower edges that extend in a single line and being formed of one integral piece of single ply paper, there being a strip of fabric material attached to said interior surfaces and coextensive with said lower edges.

JOHN F. AMES.
